UNITED STATES PATENT OFFICE

CLAUDE L. FRIEL, OF CHICAGO, ILLINOIS

ROTARY IMPRINTING PRESS

Application filed August 19, 1929. Serial No. 386,784.

This invention relates to machines for imprinting additional matter, for example a firm's name, a serial number or similar desired information, upon printed sheets such as are used in the forming of check books. A single sheet contains a plurality of printed check forms and it is therefore necessary to print the varying additions to said forms a plurality of times upon each sheet and in the correct order as to serial number. Applicant has designed machines of this nature which are now generally in use, one of said machines being disclosed in Patent No. 1,549,533 of August 11, 1925. The bed and cylinder press, to which the patent relates, performs the desired work by the use of a differentially reciprocal bed which carries the type form and cooperates with a cylindrical impression member.

The purpose of the present invention is to provide a machine for performing the work of the patented machine at a more rapid rate, which is of a rotary character, and avoids the inertia of reciprocating parts, and requires less mechanism.

An object of the invention is to provide a machine having a rotary printing form carrying member with means for automatically adjusting the form on the carrier between successive impressions whereby these impressions are received at different areas upon a sheet carried by a coating rotary cylinder or other suitable paper carrying or platen member. A further purpose of the invention is to provide for varying at will the extent to which the type form is shifted on its carrying cylinder. Thus the press is adapted for work upon sheets and checks of various size.

The purposes of the invention are accomplished by means of a construction such as illustrated in the drawings, in which:

Figure 1 is a plan view of the improved press.

Fig. 2 shows the press in side elevation.

Fig. 3 is a detail in transverse section of the type carrying cylinder and cooperating impression cylinder.

Fig. 4 is a sectional view taken on the line 4-4 of Fig. 3.

Fig. 5 is a detailed sectional view of the type carrying cylinder taken on the line 5-5 of Fig. 4.

Fig. 6 is a sectional detail taken on the line 6-6 of Fig. 5 illustrating means for adjusting the cam which regulates the positioning of the type holder on the type carrying cylinder during successive rotations of the latter.

Fig. 7 is a fragmentary detailed view 60 illustrating the mounting of the type form.

Fig. 8 is a sectional detail taken on the line 8-8 of Fig. 7.

Fig. 9 is a sectional detail taken on the line 9-9 of Fig. 7;

Figs. 10 and 11 are detailed views of the type of wedge forms suitable for use in this press.

Figs. 12 and 13 illustrate the holder for a numbering device.

The principal features of the construction illustrated are a rotating type cylinder and cooperating platen cylinder which are driven in opposite directions. The platen cylinder receives the paper to be printed upon sheet 75 by sheet and causes the paper to receive an impression during several rotations of the cylinders before the latter are separated and the paper removed from the platen cylinder. In order that a series of like impressions may be received by each sheet of paper, the type cylinder is provided with an adjustable type form or carrier which automatically takes different positions between impressions with reference to the supporting drive shaft for this cylinder. This general arrangement will be referred to more in detail in the following description which also details the specific means employed for varying the degrees of movement of the type carrying form 90 with reference to its continuously rotating supporting means.

Referring to Figures 1 and 2, the frame 1 of the press has journaled therein a drive shaft 2 receiving power from a pulley 3 and provided with the customary hand wheel 4 for convenience in turning the drive shaft and mechanism operated thereby. Fixed to the drive shaft is a pinion 5 meshing with a gear 6 fast to shaft 7 of the impression cyl-

inder 8, the platen portion of which is indicated at 9. Gear 6 also meshes with a gear 10 secured to shaft 11 which supports the type carrying cylinder 12. The gear 10 is preferably connected with shaft 11 by being adjustably mounted upon the flange of hub 13 which is keyed to shaft 11. The purpose of allowing for adjustment is to advance or retract the type carrying cylinder with respect to the platen cylinder in order to vary as a whole the places of impression upon the paper.

In order to accomplish the principal purpose of this invention which is to make the same impression a plurality of times in different places upon the same sheet of paper at successive rotations of the type carrying cylinder and the cooperating platen cylinder, a type carrier forming part of the cylinder 12 is arranged to be automatically shifted angularly with reference to supporting shaft 11 during each rotation of the cylinder and after each impression.

Automatic adjustment of the type carrier 14 is provided for by mechanism shown in detail in Figures 3 and 4. This mechanism includes a fixed pinion 15 cut in one of the bearings 16 for shaft 11. Meshing with the pinion 15 is a gear 16 journaled in a support 17 fast to shaft 11. A carrying shaft 18 for gear 16 also carries a pinion 19 meshing with a gear 20. The gear 20 is secured to a sleeve 21 freely rotatable with reference to shaft 11 and carrying a cam 22. Since the gear 16 rolls on the fixed pinion 15, the cam 22 is rotated at a definite ratio to cylinder 12. As illustrated, the cam makes one rotation to each four rotations of the cylinder. The cam 22 cooperates with the roller 23 on a bell crank 24, one arm of which is a segment gear 25. This segment gear meshes with another segment gear 251 which is secured to the type carrying member 14 which is in the form of a yoke and includes the end plates 26 and counterweight 27.

The cam 22, Fig. 3, rotates oppositely to the rotation of the type carrying cylinder 12 and at a slower rate. Therefore since this cam operates the segment bell crank member 24 rocking it outwardly after each impression, the type holder will be adjusted with reference to shaft 11 after each impression.

The first two adjustments of the type carrier 14 will be in the direction of rotation of the cylinder 12 and its shaft 11, and a third adjustment will, by a reverse motion, effect the restoring of the type carrier to its original position. This reverse motion takes place when the roller 23 rides from the high part of the cam to the low part.

In order to adjust the throw of cam 22 so that the angular adjustment of the type carrier 14 may be varied to suit different sizes of paper or impression forms, a hand adjustment such as illustrated in Fig. 6 is

provided. This consists of a manually operated wheel 29 which is provided with an interiorly threaded hub in order to be shiftable longitudinally along the sleeve 30 which is rigid with the gear carrying sleeve 21. The sleeve 21 is provided with a pair of channels 31 within which are slidable the wedge members 32 having tongues 33 engaging an annular groove 34 in the hub of wheel 29. The cam 22 is provided with inclined ways 35 which are slidably engaged by wedge members 32 upon the adjustment of the wheel 29 and the cam therefore is shifted inwardly or outwardly from the center of shaft 11 upon an adjustment of wheel 29. The cam is guided in this adjustment by pins 36. The cam is retained in its adjusted position by means of a clamp screw 37.

For the purpose of facilitating change of forms in the impression cylinder 12, the sheet feeding table 38 is hinged to its support at 39 as indicated in Fig. 2 and may be swung to the broken line position 40. Gauges and guides 41 and 42 are provided for the paper received by table 38 as is customary. The paper is removed from the table 38 and received on the cylinder 8 as required by means of the gripping fingers 42. These fingers are operated at the proper time by means not fully illustrated in the drawings.

In the particular machine illustrated, the type form member 14 is adjustable on the cylinder 12. Its first position, when the fresh sheet is received by the cylinder 8 is the position 141 shown by dotted lines in Fig. 3. Second position is the full line position 14 and the third is the dotted line position 142. When all three impressions have been made, the fourth rotation of cylinder 12 takes place while the roller 23 is at the low part of cam 22. During this revolution of the cylinder, the printed sheet is received by the delivery device 43 (Figs. 1 and 2). Also during this fourth rotation of the cylinder 12 and the corresponding rotation of cylinder 8 the two

cylinders are separated by mechanism which raises cylinder 8 so that no impression will take place at this time. For this purpose cylinder 8 is provided with journals 44 which are slightly shiftable in the machine frame under the action of box cam 45 (Fig. 2) carried by gear 46 meshing with a pinion 48 on shaft 11. An arm 50 carries a roller at its ends for engaging the groove in the cam 45 and is also rigid within eccentric 51 fitting within the member 52 to shift the journals 44 of the impression roller 8. The impression roller 8 is normally urged toward the type carrying cylinder 12 by spring 53.

Ink distributing rolls are indicated in Fig. 2 at 54 and 55 respectively.

In operation of the press, a sheet of paper received by the impression cylinder 8 receives a series of impressions one for each rotation of the impression cylinder 9 and the

type supporting cylinder 12, the type carrying member 14 of the latter cylinder being shifted after each impression by means of the cam 22 as previously described in order that the impressions will each be at a different and particular location upon the sheet.

After the third impression the cylinders are separated so that at each fourth revolution of the cylinders the type form carrying cylinder 12 does not make an impression while the paper is removed from its carrying cylinder 8 and deposited into the receiver 43.

Although but one specific embodiment of this invention has been herein shown and described, it will be understood that numerous details of the construction shown may be altered or omitted without departing from the spirit of this invention as defined by the following claims.

20 I claim:

1. A rotary printing press of the class described comprising a type form carrying cylinder, means for continuously rotating said cylinder, a platen member cooperating with 25 said cylinder, a type form carrying element adjustably mounted upon said cylinder, means for automatically adjusting said type form carrying element upon the cylinder between the making of successive impressions, 30 said means for automatically adjusting the type carrying element having a varying throw, a manually operable member arranged for predetermining the extent of said throw, said means for varying the throw comprising 35 a radially shiftable cam, and the manual adjusting means comprising wedging elements for forcing the cam outwardly or drawing it inwardly.

2. A printing press of the class described 40 comprising cooperating type carrying and platen cylinders with means for continuously rotating the same, said type carrying cylinder being provided with a type carrying form, and means for automatically advancing and 45 retracting said type carrying form angularly around the cylinder and with reference to the rotation of the cylinder as a whole.

3. A printing press of the class described 50 comprising cooperating type carrying and platen cylinders with means for continuously rotating the same, said type carrying cylinder being provided with a type carrying form, means for automatically advancing and 55 retracting said type carrying form with reference to the rotation of the cylinder as a whole, and means for shifting the platen cylinder after a predetermined number of rotations, 60 said platen cylinder being provided with paper receiving and releasing means operable when the cylinders are separated.

4. A rotary printing press comprising a 65 paper carrying platen cylinder, a cylinder having a type form carrying element thereon, means for driving said cylinders at the same peripheral speed, and means for effecting

relative angular adjustment between said type form carrying element and the platen cylinder between successive impressions whereby a sheet of paper carried by said platen cylinder will receive successive impressions upon different portions of its surface.

5. A rotary printing press comprising a paper carrying platen cylinder, a cylinder having a type form carrying element thereon, means for driving said cylinders at the same peripheral speed, means for angularly adjusting forwardly and backwardly said type form carrying element around its supporting cylinder between successive impressions to bring said type form carrying element opposite different surfaces on said platen cylinder upon successive impressions.

Signed at Chicago this 2nd day of August, 1929.
